Patented Aug. 30, 1921.

FIG. 4.

FIG. 3.

FIG. 5.

Inventor
Samuel L. Adelson
By his Attorney
Leaune Block

UNITED STATES PATENT OFFICE.

SAMUEL L. ADELSON, OF NEW YORK, N. Y.

INCANDESCENT-LAMP LOCK.

1,389,112.

Specification of Letters Patent. Patented Aug. 30, 1921.

Application filed March 25, 1920. Serial No. 368,721.

To all whom it may concern:

Be it known that I, SAMUEL L. ADELSON, a citizen of the United States of America, residing at New York city, county and State of New York, have invented certain new and useful Improvements in Incandescent-Lamp Locks, of which the following is a full, clear, and exact description.

This invention relates to improvements in 10 electric light bulb sockets, one of the objects being to provide a comparatively simple and inexpensive socket from which a bulb cannot be removed, excepting by an authorized person.

15 I will now proceed to describe my invention in detail, the novel features of which I will finally claim, reference being had to the accompanying drawing, wherein:—

Figure 1 is a sectional view, partly in elevation of an embodiment of my invention;

20 Fig. 2 is a detail view illustrating some of the elements of my invention;

Fig. 3 is a top plan view of the bulb-engaging member;

25 Fig. 4 is a side elevation thereof; and

Fig. 5 is a top plan view of the rotatable sleeve which forms part of my invention.

As herein arranged my invention consists of a bulb holding member 6 made up of a 30 head 7 and a threaded socket 8, a support for the said bulb holding member being indicated by 9, which is comprised of a plug portion 10, to engage a standard socket 11, and a threaded sleeve 12 to be engaged by

35 the socket portion 8 of the bulb support. Further elements consist of a shell member 13 carried by the plug member or portion 10, and a sleeve 14 which is rotatably supported by the shell 13, and arranged to

40 engage the socket 11. As can be seen, the plug carries a conductor 15 to contact with the terminal 16 of a bulb 17, the upper end of said conductor contacting with the terminal 18 of the socket 11. Un- 45

der ordinary conditions the bulb holder consisting of the head 7 and socket 8 will freely rotate within the shell 13, hence after the bulb is screwed thereinto said bulb cannot be removed for the reason that said bulb

50 holder will rotate. In other words, should the bulb be rotated in a direction for the removal thereof the socket portion 8 will be screwed off the threaded portion 12 of the plug 10 and rest upon the shoulder 19 of the shell 13 (see dotted lines Fig. 1), after which it will rotate, should the bulb be ro-

tated; hence said bulb cannot be removed. To cause the socket to engage the threaded sleeve 12, it will be moved upwardly, should it be positioned as shown by dotted lines 60 Fig. 1. When the bulb support is screwed upwardly to its full extent, the conductor 15 will contact with the terminal 18 on the bulb and so far as these elements are concerned the circuits will be complete. 65

To remove the bulb the bulb support will be held against rotation by a shiftable device, consisting of the sleeve 14. Under ordinary conditions the sleeve 14 will be secured to the socket 11 by a clamp 20 which 70 acts to hold the sleeve against downward movement. The clamp is operated by a screw 21 having a head 22 of special shape requiring a key of a similar shape to operate it to release or tighten the clamp. So long 75 as the sleeve 14 is in its raised position, the socket holder will freely rotate and the bulb cannot be removed.

To remove the bulb, the sleeve 14 will be shifted or lowered to cause a pin 23 carried thereby to engage one of a number of notches 24 in the head 7 of the bulb holder, after which the bulb can be removed, for the reason that said bulb holder will be held 80 against rotation. 85

As can be seen the shell 14 is provided with an angularly disposed opening 25 through which the pin 23 passes into an elongated slot 26 in the flange portion 27 of the plug 10. The slot 26 in the flange 27 90 extends from the upper surface to the lower surface thereof. When the shell 14 is rotated, as per the arrow in Fig. 2, pin 23 will pass through slot 26 and engage a notch 24 in the head 7 after the bulb has been rotated 95 to a small degree. After the pin 23 engages a notch, the bulb 17 can be removed as the bulb holder will be held against rotation. The notches 24 will be slightly undercut, as at 28, to prevent any possibility of the pin 100 being forced out by undue force.

To release the clamp in order that sleeve 14 can be moved downwardly, a special key, to fit the special head of the screw, will be employed. 105

Having described my invention, what I claim and desire to secure by Letters Patent is:—

1. In combination with a standard socket for electric light bulbs, a plug to engage the 110 threaded bushing of said socket, a threaded sleeve carried by the plug, a rotatable bulb

support consisting of a threaded socket member engaging said threaded sleeve, a head carried by the socket member, and provided with a plurality of notches, a rotatable sleeve 5 surrounding the plug and bulb-support, a pin carried by the sleeve to engage said notches to prevent the rotation of the bulb-support, and releasable means to secure said sleeve against rotation when said sleeve is 10 not in use to prevent rotation of said bulb-support.

2. In combination with a standard socket for electric light bulbs, a plug to engage the threaded bushing of said socket, said plug 15 having a slot in the periphery thereof, said slot being located at an angle relative to the axis of the plug, a threaded sleeve carried by the plug, a rotatable bulb-support consisting of a threaded socket member 20 engaging said threaded sleeve, a head carried by the socket member having a plurality of notches therein, a shell member carried by the plug having a slot to coincide with the slot in the wall of said plug, a sleeve rotatably supported by said shell-member adapted 25 for movement longitudinally thereof, a pin carried by the sleeve and passing through the slot in the shell member and into the alining slot in the plug, arranged 30 to engage a notch in the head member when said sleeve is moved downwardly, and releasable means to lock the sleeve against movement when said sleeve is not in use to prevent rotation of the bulb support.

3. In combination with a standard socket 35 for electric light bulbs, a plug to engage the threaded bushing of said socket, said plug having a slot in the periphery thereof, said slot being located at an angle relative to the 40 axis of the plug, a threaded sleeve carried by the plug, a rotatable bulb support con-

sisting of a threaded socket member, engaging said threaded sleeve, a head carried by the socket member having a plurality of notches therein, a shell member carried by 45 the plug having a slot to coincide with the slot in the wall of said plug, a sleeve rotatably supported by said shell member adapted for movement longitudinally thereof, a pin carried by the sleeve and passing 50 through the slot in the shell member and into the alining slot in the plug arranged to engage a notch in the head member when said sleeve is moved downwardly, and means to secure the sleeve to the standard socket 55 when said sleeve is not in use to prevent rotation of the bulb support.

4. In combination with a standard socket for electric light bulbs, a sleeve carried thereby and movable longitudinally thereof, 60 releasable means to secure the sleeve to said socket, a plug member within the sleeve to engage said socket, a threaded sleeve carried by said plug member, a rotatable bulb support, consisting of a threaded socket 65 engaging the sleeve, carried by said plug, a notched head carried by the bulb support, a shell carried by the plug inclosing said bulb support, the shell in turn being inclosed by said first named sleeve, and means 70 carried by the first named sleeve arranged to engage the notches in the head on the bulb support, when said sleeve is released and moved downwardly to prevent rotation 75 of said bulb support.

Signed at New York city, N. Y., this 24 day of March, 1920.

SAMUEL L. ADELSON.
